FOOTBALL DOWN INDICATOR

Ralph E. Rice, Stewartville, Minn.

Application June 7, 1941, Serial No. 397,118

2 Claims. (CL. 40—133)

This invention relates to a football down indicator, and has for the primary object the provision of a portable device of the above stated character which may be conveniently handled to facilitate the quick and easy manual arrangement thereof from one place or position of play to another on a football field and includes characters or numbers, representing the downs in a football game, any one of which may be positioned opposite to the spectators to indicate the particular down and may be easily read from a maximum distance either in day or night time by the spectators.

Another object of this invention is the provision of an electric illuminating means for the device, the source of electric energy being carried thereby or if desired the illuminating means may be electrically connected to an electric system utilized in the illumination of the playing field.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a football down indicator constructed in accordance with my invention.

Figure 2 is a vertical sectional view illustrating the device, and the electric illuminating means therefor.

Figure 3 is a sectional view taken on the line 3—3 of Figure 1.

Figure 4 is a sectional view taken on the line 4—4 of Figure 1.

Figure 5 is a bottom plan view illustrating the device.

Referring in detail to the drawings, the numeral 5 indicates as an entirety a substantially rectangular shaped casing or box which includes side walls 6, a bottom wall 7 and a top wall or cover 8. The box or casing being of the shape specified presents four sides thereto and said sides have stenciled or otherwise formed therein numbers ranging from 1 to 4 to indicate the downs in a football game. The numbers are backed by plates 9 of translucent material held in place within the box or casing by metallic strips 10 removably secured to the inner faces of the walls by fasteners 11. Said fasteners are preferably in the form of bolts provided with wing nuts. The backing plates are preferably of a differen-

tiating color from the walls of the box or case so that the characters or numbers can be conveniently read for a maximum distance by spectators of the football game.

The side walls of the box or casing are preferably removably secured to the bottom wall 7 and the top wall or cover 8 by fasteners 12. Also it is preferable that the vertical edges of the side walls be mitered, as shown in Figure 4, so that when assembled neat appearing joints will be presented thereto.

By referring to Figure 2 it will be seen that the top wall or cover 8 is of a flanged type so as to fit within the side walls and overlie the upper edges thereof. Sight openings 13 are provided in the top wall or cover 8 and are arranged in groups of numbers corresponding to the numbers of the side walls so that the operator employing the device can readily determine the number of a particular side of the box or casing without the tilting thereof from a vertical position which greatly assists the operator in presenting to view the proper number designating the down in the football game to the spectators.

The top wall or cover 8 is provided with a centrally arranged opening communicating with a recess 14 opening outwardly through the inner face of said top wall or cover for the reception of an anchoring plate 15 on which is formed a screw threaded ferrule 16 located within said opening. The anchoring or base plate 15 is secured within the recess 14 by fasteners 17 and is provided with an electric lamp socket 18 arranged within the ferrule 16 and removably supports an electric lamp 19 within the box or casing.

Also carried by the base plate 15 is a reflector 20 for the electric lamp. The electric lamp may be of any selected color and when illuminated will efficiently illuminate the characters or numbers of the side walls in order that they may be readily read by the spectators from a maximum distance at night time. Also the sight openings 13 will be illuminated by the electric lamp in order that they may be observed easily by the operator of the device at night time.

A handle 21 preferably in the form of a flashlight construction is threaded in the ferrule 16 and contains the usual dry cells or batteries 22 for furnishing electric energy to the electric lamp 19. However, the handle 21 may have the batteries omitted and the electric lamp suitably connected to an electric extension cord so that the device may be plugged into an ordinary outlet of an electric system used in the illumination of the playing field. It being understood that

the extension cord may be of such a length as to permit the operator to move the entire device from one place to another on the playing field.

The bottom wall 7 is equipped with a sleeve 23 having a base flange 24 secured to said bottom wall by fasteners 25. The sleeve 23 receives an impaling pin or leg 26 pointed, as shown at 27, to facilitate its insertion into the ground. The length of the impaling pin or leg may be such as to support the box or casing at a proper height 10 for viewing by the spectators.

The box or casing may be constructed of any material suitable for the purpose, such as wood, metal or a composition of materials. This also applies to the sleeve 23 as well as the impaling 15 pin or leg. The construction set forth in reference to the box or casing will permit the latter to be easily taken apart should it be necessary to replace any part therein.

Further, it will be seen from the foregoing description taken in connection with the accompanying drawings that an indicator for a special purpose has been provided and one that will be extremely convenient for the operator to employ and position so that spectators either in the night or daytime can be informed from a maximum distance the particular down within a football game, also showing clearly by the positioning of the device on the playing field where the down occurs.

While I have shown and described the preferred embodiment of my invention, it will be understood that minor changes in construction,

combination and arrangement of parts may be made without departing from the spirit and scope of the invention claimed.

Having thus described my invention, what I claim is:

1. In a football down indicator, a substantially rectangularly shaped box including side, top and bottom walls and said side walls being stenciled to form numbers designating the downs in a football game, an impaling pin secured to the bottom wall of the box, said top wall having a recess and an opening communicating with said recess, a base plate secured in the recess and including a screw threaded ferrule located in the opening, an electric lamp socket carried by the base plate, a reflector carried by the base plate, an electric lamp carried by said socket, and a handle for the support of the box threaded in the ferrule and including means for the illumination of the electric lamp.

2. In a football down indicator, a box having the sides thereof stenciled to provide numbers designating the downs in a football game, an impaling pin secured to the box, said box including an opening and a recess, a base plate secured in the recess and including a threaded ferrule extending into the opening, an electric lamp socket carried by the base plate, an electric lamp carried by the socket, a handle threaded in the ferrule for the support of dry cells to furnish electric energy for the electric lamp.

RALPH E. RICE.
